UNITED STATES PATENT OFFICE.

JOHN AUGUSTUS HICKS, OF SUMMIT, NEW JERSEY, ASSIGNOR, BY
MESNE ASSIGNMENTS, TO THE AUTO STOPPER COMPANY, OF
NEW YORK, N. Y.

MACHINE FOR BOTTLING LIQUIDS.

SPECIFICATION forming part of Letters Patent No. 785,001, dated March 14, 1905.

Application filed July 27, 1904. Serial No. 218,342.

To all whom it may concern:

Be it known that I, JOHN AUGUSTUS HICKS, a citizen of the United States, and a resident of Summit, in the county of Union and State of New Jersey, have invented certain new and useful Improvements in Machines for Bottling Liquids, of which the following is a specification.

My invention relates to machines for bottling liquids; and it consists in certain elements and combinations of elements fully specified and claimed hereinafter.

In order that those skilled in the art to which my invention appertains may understand, construct, and use my invention, I will proceed to describe it, referring to the accompanying drawings, forming part of this specification.

Figure 1 is an elevation of a bottling-machine to which I attach my invention. Fig. 2 is a longitudinal central section on line X X, but without the framework. This view is taken looking from right to left of the drawing Fig. 1. Fig. 3 is a longitudinal central section of the bottling-head looking from the front of the machine as illustrated in Fig. 1 and showing my invention in enlargement of Figs. 1 and 2 without lettering and describing the parts of the machine which are common to most bottling-machines and well known to those skilled in the art of bottling liquids, whether under pressure or not.

I will describe the particular parts which are novel and my invention.

A is the usual bottling-head, secured in cross-frame B by nuts C. D is the taper tube which runs vertically through this head A, and through this a plunger E operates up and down. This tube D has no openings into its inner circumference, as is the usual custom, for the entrance of the fluid into it in its passage to the bottle which is being filled nor for the exit of the air, which escapes from the bottle while it is being filled, called by bottlers "sniffing." On this account the tube D is smooth and unobstructed throughout its whole length, and therefore cannot abrade the cork which is forced through it by the plunger in corking the bottle after

it is filled. In ordinary bottling-machines this tube D is both a filling and corking tube, 50 while in my invention it is only a corking-tube, the filling being done by another method, which I will now describe.

F is an opening in the bottling-head threaded to receive a threaded pipe which connects 55 with the fluid-supply tank in a well-known manner, said pipe having the usual valve to regulate the flow of fluid.

G, Fig. 3, is a small passage leading from the opening F to the bottom of the bottling-head 60 and not, as is usual, to the tube D. H is an opening in the bottling-head for the discharge of air from the bottle while being filled and has a passage J to connect it with the bottom of the bottling-head instead of to the tube D, 65 as is usual. Into the opening H is screwed a discharge-pipe having a valve to regulate the air-discharge, usually called the "sniffing-valve." At the bottom of the bottling-head A a flange K is fastened by screws L and having an opening in its center equal to the diameter of the lower end of the taper tube D. A washer M, located between the bottom of the bottling-head and the flange K, separates the two a slight distance, so that a space is provided for 70 the entrance into it of fluid through passage G and the exit of air to passage J. A rubber gasket N is secured beneath flange K by a flanged nut O. This gasket N has a hole in it of proper size to fit the top of bottle which is 80 to be filled and makes a tight joint between flange K and the bottle-mouth. The tube D carries the stopper when the machine is being operated to fill bottles and cork or seal them.

In Fig. 3 is shown a bottle being in position to be filled, with the stopper in the tube D. Q is the bottle. R is the sealing-cap secured upon the bottle-mouth and having an opening in the top surface centrally of said surface and of smaller diameter than the diameter of the bore of the bottle.

The gasket N is shown compressed upon a shoulder S on the bottle-neck to make a tight joint between the bottling-head and the bottle. Fig. 4 shows a top view of the flange K. 95

T is the valve which opens or closes the

connection of the bottling-head passages G with the source of supply for the fluid, usually under great pressure.

Fig. 1 shows the bottling-head and its various parts compressed upon the bottle-mouth by means of foot-lever U and its connections with the sliding frame B, which carries the bottling-head in the usual manner.

The operation of filling a bottle by the bottling-machine as illustrated in the drawings is as follows: The valve T being closed, the traveling cross-head, which carries the plunger E, being at its topmost limit of throw, and the lower end of the plunger above the top of the bottling-head, a stopper of larger diameter than the top of the tube D is placed in the tube D and the plunger forced down upon it, driving it downward in the said tube and squeezing it to the diameter of the lower part of the taper tube D to about the position shown in Fig. 3. The bottle to be filled is then placed under the bottom of the bottling-head and tube D and resting on the table in a cup Y. The bottling-head A is then brought down upon the bottle Q by the foot-lever U and its connections to said head, so that the gasket N rests upon the bottle Q firmly, making a tight joint, as shown in Fig. 3. The valve T is then opened and the fluid under pressure is led into the bottle Q through the passage G and the bottle filled nearly to the top, the air which was in the said bottle escaping through passage J and the sniffing-valve above referred to and which is a well-known device and is a spring-valve set to the desired pressure. The plunger is then forced downward by the hand-lever Z and its connections until the stopper has entered the bottle-mouth to the desired extent. In the bottle

shown it is forced through the opening in the 40 bottle-cap and beneath it. The valve T is then closed, and the pressure in the bottle Q forces the stopper upward against the under side of the bottle-cap and seals the bottle by pressure from within the bottle. The bottle is then 45 removed and the operation is repeated with another bottle.

As there are no openings in the circumference of tube D, there can be no abrasion of the stopper, as in the case with bottling-tubes 50 which are perforated by the filling and the air-discharge openings and are both filling and corking tubes.

Having now fully described my invention and the manner in which I have embodied it, 55 what I claim as my invention, and desire to secure by Letters Patent, is—

In a bottling-head for bottling-machines, the combination consisting of the corking-tube as D; a flange-plate secured to the base 60 of said bottling-head, surrounding the base of said corking-tube, and forming a space between the said flange and the base of said bottling-head; passages for conveying fluid and for air-discharge leading to and from the 65 space between said flange and the base of said corking-tube, all combined and arranged substantially as specified, whereby the fluids in their passage to and air in its passage from a vessel being filled, passes beneath the corking- 70 tube into the bottle substantially as specified.

Signed at New York, in the county of New York and State of New York, this 25th day of July, A. D. 1904.

JOHN AUGUSTUS HICKS.
